HENRY H. ROCKWELL, OF NEW LONDON, CONNECTICUT, ASSIGNOR TO HIMSELF, HENRY L. BACON, AND JOHN H. LATHAM, OF THE SAME PLACE.

Letters Patent No. 71,648, dated December 3, 1867.

IMPROVED SAFETY-STRAP FOR BRIDLES.

The Schedule referred to in these Letters Patent and making part of the same.

TO ALL PERSONS TO WHOM THESE PRESENTS MAY COME:

Be it known that I, HENRY H. ROCKWELL, of the city and county of New London, and State of Connecticut, have made a new and useful invention, having reference to bridles or headstalls, and which may be termed a Safety-Strap or apparatus for checking or stopping a horse; and I do hereby declare the same to be fully described in the following specification, and represented in the accompanying drawing, which exhibits a side view of it.

In such drawing, A and B denote two leather or other straps connected by a buckle, a, fastened to one end of the shorter of such straps. On each of the said straps is a disk, C, which may be of leather or other suitable material, and may slide on the strap. Each strap, at its outer end, has a ring, D, fastened to it.

The purpose of the above-described apparatus is to arrest a horse, or prevent him from running away, while being driven. In using it, both straps are to be passed through the rings of a bit when in the mouth of the horse. The longer one, after having been carried over the head or neck of the horse, is to be buckled to the shorter, so as to bring both the disks close up to the bit in order to support it. The driving-reins are next to be buckled or fastened to the rings of the straps. When the rein or reins are pulled on, the bit will be drawn closely upward into the mouth of the animal, and against the angles of junction of his lips, and thus he may be checked or stopped, as occasion may require.

The apparatus may constitute part of a bridle or headstall, and be used instead of the ordinary bit-hangers thereof.

It should be observed that the disks are for preventing the bit from being pulled out of the mouth of the horse, or too low therein. The rings hold the disks on the straps, and also serve to enable the reins to be connected thereto.

When forming part of a riding-bridle or headstall of a harness, the apparatus may be made with a single strap to go over the head of the horse. I prefer, however, to construct it with two straps, as described, particularly when it is to be used as auxiliary to a bridle or headstall.

I am aware of the subject of the United States Patent No. 43,308, and therefore do not claim such. My invention differs therefrom in having disks applied to the strap or straps and over the rings, whereby the bit is supported on strap or straps by such disks, and is prevented thereby from dropping too far in the mouth of the horse. The disks render common bit-hangers unnecessary, and thereby greatly simplify the apparatus.

I therefore claim the arrangement and combination of the disks with the strap or straps and the rein-rings thereof, the said disks being for the purpose and to operate as specified.

HENRY H. ROCKWELL.
